CIGARETTE CASE OR THE LIKE

Leo K. Stupell, New York, N. Y.

Application June 21, 1945, Serial No. 600,799

5 Claims. (Cl. 220—83)

1

This invention relates to improvements in cigarette cases and has for its object the provision of an improved cigarette case made of a combination of synthetic plastic and metal, simple in construction, light in weight, easy to open, and which will provide an efficient container for cigarettes and the like.

Further objects will be apparent from the specification and drawings in which,

Fig. 1 is a top plan view of my improved cigarette case,

Fig. 2 is a side view thereof,

Fig. 3 is a sectional view along line 3—3 of Fig. 1.

Fig. 4 is a sectional view along the line 4—4 of Fig. 1.

Fig. 5 is a front plan view, and

Fig. 6 is a plan view of the rear of the case.

Fig. 7 is a fragmentary section along the lines 1—7 of Fig. 4.

In the drawings, the numeral 10 indicates the metal frame of my improved cigarette case, 11 being the line of meeting of the ends of the frame, 12 is the bottom flange of the frame 10 which is integral therewith, this flange receiving the bottom or base of the case made of plastic 13.

14 indicates the plastic top on which is positioned the metal reinforcement 15 having the rear flange 16 and the front flange 20 which also acts as the closing element of the case, said part 20 engaging the small metal protuberance 21.

17 indicates the hinge of the case which is shown in Figs. 1 and 6, the hinge consisting of five cylindrical members shown joined by the pin 17b. It should be noted that of the five hinge elements, the two end elements and the intermediate element are formed integral with the metal reinforcement 17a on the rear of the case and the other two intermediate elements of the hinge are formed integral with the continuation of the top member 15.

19 more clearly shown in Fig. 4 are lugs integral with the rear plate 17a and which join this plate to the main metal frame 10.

It will be noted that the metal frame of the case apart from the pivot pin 17b is made up by three metal parts only, one the rectangular frame 10, two the top metal reinforcing piece 15, from the ends of which part of the hinge 17 is constituted, three, the rear supporting piece 17a, the two end portions of the hinge and the middle section being integral with the plate 17a.

Lugs 18 are formed upon the plate 15 as shown to securely fasten this plate to the top plastic member 14.

2

It will be seen from this form of construction that a cigarette case is formed which is compact and sturdy having as few parts as possible and capable of withstanding continued use and strain.

5. In the drawing, the top middle plate 15 (see Fig. 1) is shown without ornamentation, but without weakening the case this plate 15 can be readily perforated to show one or a series of initials clearly adding to the decorative effect of the same.
10. It is apparent that further modifications can be made in this construction without departing from the spirit of my invention.

I claim:

1. A cigarette case or similar container consisting of a rectangular metal frame forming the side walls of the case and having an integral bottom flange, a bottom for said case held in place by said bottom flange, a top for said case, a metal plate mounted on the outer surface of the top, and an auxiliary rear plate adjoining the ends of the rectangular frame, one end of said metal plate constituting a closing element together with a registering integral part of the metal frame, the other end of the metal plate constituting part of the hinge element for the top of the case, said auxiliary rear plate having integral parts forming part of said hinge element.

2. A cigarette case or similar container consisting of a rectangular metal frame forming the side walls of the case and having an integral bottom flange, a plastic bottom for said case held in place by said bottom flange, a plastic top for said case, a metal plate mounted on the outer surface of the top, and an auxiliary rear plate adjoining the ends of the rectangular frame, one end of said metal plate constituting a closing element together with a registering integral part of the metal frame, the other end of the metal plate constituting part of the hinge element for the top of the case, said auxiliary rear plate having integral parts forming part of said hinge element.

3. A cigarette case or the like consisting of a rectangular metal frame having its ends meeting in the rear of said case, forming the side walls of the case, and having an integral bottom flange, a plastic bottom for said case held in place by said bottom flange, a plastic top for said case, a rectangular metal plate mounted on the outer surface of the top, and an auxiliary rear plate adjoining the ends of the rectangular frame, one end of said metal plate constituting a closing element together with a registering integral part of the metal frame, the other end of the metal plate constituting part of the hinge element for the top of

the case, said auxiliary rear plate having integral parts forming part of said hinge element.

4. A cigarette case or the like consisting of a rectangular metal frame having its ends meeting in the rear of said case, forming the side walls of the case, and having an integral bottom flange, a plastic bottom for said case held in place by said bottom flange, a plastic top for said case, a rectangular metal plate mounted on the outer surface of the top, and an auxiliary rear plate adjoining the ends of the rectangular frame, one end of said metal plate constituting a closing element together with a registering integral part of the metal frame, the other end of the metal plate constituting part of the hinge element for the top of the case, said auxiliary rear plate having integral parts forming part of said hinge element, said rectangular metal plate being provided with one or more cut-outs to form initials on said case.

5. A cigarette case or the like consisting of a rectangular metal frame having its ends meeting in the rear of said case, forming the side walls of the case, and having an integral bottom flange, a plastic bottom for said case held in place by said bottom flange, a plastic top for said case, a sub-

stantially U-shaped rectangular metal plate mounted on the outer surface of the top, and an auxiliary rear plate adjoining the ends of the rectangular frame, one end of said metal plate constituting a closing element together with a registering integral part of the metal frame, the other end of the metal plate constituting part of the hinge element for the top of the case, said auxiliary rear plate having integral parts forming part of said hinge element, said rectangular metal plate partially covering the plastic top.
